US0D1003927S

(12) **United States Design Patent** (10) Patent No.: **US D1,003,927 S**
(45) Date of Patent: ** Nov. 7, 2023

(54) **DISPLAY SCREEN OR PORTION THEREOF WITH ANIMATED GRAPHICAL USER INTERFACE**

(71) Applicant: **BELJING XIAOMI MOBILE SOFTWARE CO., LTD.**, Beijing (CN)

(72) Inventors: **Yanan Zhang**, Beijing (CN); **Haixu Lu**, Beijing (CN)

(73) Assignee: **BELJING XIAOMI MOBILE SOFTWARE CO., LTD.**, Beijing (CN)

(**) Term: **15 Years**

(21) Appl. No.: **35/513,376**

(22) Filed: **Sep. 28, 2021**

(80) **Hague Agreement Data**

Int. Filing Date: **Sep. 28, 2021**

Int. Reg. No.: **DM/218155**

Int. Reg. Date: **Sep. 28, 2021**

Int. Reg. Pub. Date: **Jan. 14, 2022**

(30) **Foreign Application Priority Data**

Mar. 29, 2021 (CN) 202130172622.3

(51) **LOC (14) Cl.** **14-04**

(52) **U.S. Cl.**

USPC **D14/485**
